No. 662,015.

Patented Nov. 20, 1900.

LA VERNE W. NOYES.
DRIVING GEAR FOR WINDMILLS.

(Application filed June 18, 1900.)

(No Model.)

UNITED STATES PATENT OFFICE.

LA VERNE W. NOYES, OF CHICAGO, ILLINOIS.

DRIVING-GEAR FOR WINDMILLS.

SPECIFICATION forming part of Letters Patent No. 662,015, dated November 20, 1900.

Original application filed March 8, 1899, Serial No. 708,191. Divided and this application filed June 18, 1900. Serial No. 20,714. (No model.)

To all whom it may concern:

Be it known that I, LA VERNE W. NOYES, a citizen of the United States, residing at Chicago, in the county of Cook and State of Illinois, have invented a certain new and useful Improvement in Driving-Gear for Windmills, of which the following is a full, clear, concise, and exact description, reference being had to the accompanying drawings, forming a part of this specification.

My invention relates to a driving-gear particularly designed for windmills, my object being to provide a structure whereby a plurality of reciprocating parts, as pump-rods, may be actuated by a single power device, as the wind-wheel.

While I have illustrated my invention as particularly applicable to a windmill, it will be understood that the invention is equally applicable to other mechanisms.

The present application is a division of an application filed by me March 8, 1899, Serial No. 708,191. In said application I have illustrated the driving-gear herein claimed as associated with a form of swiveling device whereby three reciprocating pump-rods may be operated together, and I have withdrawn from said application and claimed in the present application the features relating to the driving mechanism, retaining in said prior application the features relating to the swiveling device.

I have illustrated my invention in the accompanying drawings, in which—

Figure 1 is a view of the driving mechanism in elevation. Fig. 2 is a sectional view on line 2 2, Fig. 1. Fig. 3 is a view of the rotating cams or eccentrics. Fig. 4 is a sectional view on line 4 4, Fig. 3, showing the annuli in position.

Like letters refer to like parts in the several figures.

The wheel-shaft a is journaled within the sleeve a' , supported upon the barrel a^2 , which constitutes the turn-table which is adapted to rotate about the barrel a^5 , supported upon the upper end of a windmill-tower of any usual construction, and extending laterally from the sleeve a' are the arms a^3 a^4 , in which a shaft or axle a^4 is journaled. Upon the wheel-shaft a a plurality of cams or eccen-

trics are mounted. In the present case three such eccentrics are provided—to wit, b b' b^2 . The eccentrics are placed at one hundred and twenty degrees apart, as shown in Fig. 3, and each of the eccentrics is surrounded by a ring, which is hollow and which is provided at the inner periphery with one or more oil-holes or with a circular channel, which permits the oil to pass from the interior of the annulus or ring to the bearing-sleeves of the eccentrics. The cams b b' b^2 are encircled, respectively, by the rings or annuli b^5 b^8 b^4 . As shown more clearly in Fig. 4, an oil-hole is provided through the wall of the eccentric communicating with the channel around the inner periphery of the hollow annuli, whereby oil may be admitted into the interior of the annuli and fed thence to the eccentric as the annuli travel back and forth. Upon the shaft or axle a^4 are journaled the frames or casings c c' c^2 , each having an upper wall c^3 and a lower wall c^4 , against which the annulus corresponding thereto is adapted to roll. To the ends of the casings c c' c^2 the upper portions d d' d^2 of the pump-rods are respectively journaled. As the wind-wheel shaft rotates the cams moving within their respective annuli cause the annuli to roll back and forth, the annulus first rolling against the upper wall c^3 of the frame to raise the same and then rolling against the lower wall c^4 to lower the same. In this manner the rotation of the eccentric causes the annulus to roll successively in contact with the walls of the frame or casing, thereby reciprocating the same and imparting a reciprocating movement to the pump-rod. The upper portions d d' d^2 of the pump-rods extend downward to a point below the barrel of the turn-table, where the swiveling devices are arranged. The swiveling device may take the form shown in my application above mentioned or may be constructed in any other desired manner, and as the swiveling device forms no part of the present invention I have omitted the same from the drawings.

While I have illustrated my invention in connection with three cams, the drawings sufficiently illustrate the manner in which one, two, or a greater number of cams and inclosing annuli may be employed with the corre-

sponding number of frames or casings to ac-
tuate one, two, or a greater number of pump-
rods.

Having described my invention, what I
claim as new, and desire to secure by Letters
Patent, is—

1. In combination, a plurality of eccen-
trics, an annulus surrounding each, a recip-
rocating frame or casing for each annulus
upon the wall of which the annulus is adapt-
ed to roll, and rods or parts connected to and
reciprocated by the respective frames, sub-
stantially as described.

2. In combination, three eccentrics ar-
ranged at equal distance apart, an annulus
surrounding each, a reciprocating frame or
casing for each annulus upon the walls of
which the annulus is adapted to roll, and rods
or parts connected to and reciprocated by the
respective frames, substantially as described.

3. In combination, the shaft of a windmill,
an eccentric thereon, an annulus encircling
said eccentric, a pump-rod, and a reciprocating
part connected with the pump-rod and
having a wall against which said annulus is
adapted to roll, substantially as described.

4. In combination, an eccentric, an annulus
encircling the same and a reciprocating part
against which the annulus is adapted to roll,
said annulus having an interior oil-chamber

communicating with the periphery of said ec-
centric, substantially as described.

5. In combination, an eccentric, an annulus
encircling the same and a part against which
the annulus is adapted to roll, said annulus 35
having an interior annular channel commu-
nicating with the periphery of said eccentric,
substantially as described.

6. In combination, an eccentric, an annulus
encircling the same, and a part against which 40
the annulus is adapted to roll, said annulus
having an interior annular channel and a
communicating passage between said channel
and the periphery of the eccentric and ex-
tending completely around the inner periph- 45
ery of the annulus, substantially as described.

7. In combination, an eccentric, an annulus
encircling the same and having an annular
oil-chamber opening at the inner periphery of
the annulus, and an oil-hole passing through 50
the eccentric and communicating with said
oil-chamber, substantially as described.

In witness whereof I have hereunto sub-
scribed my name in the presence of two wit-
nesses,

LA VERNE W. NOYES.
